UNITED STATES PATENT OFFICE

144,620

DESIGN FOR A CASE FOR AN OPHTHALMIC MOUNTING

Herman F. Huttemeyer, Southbridge, Mass., assignor to American Optical Company, Southbridge, Mass., a voluntary association of Massachusetts

Application June 25, 1945, Serial No. 120,335

Term of patent 14 years

(Cl. D57—1)

To all whom it may concern:

Be it known that I, Herman F. Huttemeyer, a citizen of the United States of America, residing at Southbridge, in the county of Worcester and State of Massachusetts, have invented a new, original, and ornamental Design for a Case for an Ophthalmic Mounting, of which the following is a specification, reference being made to the accompanying drawing, forming a part thereof.

Fig. I is a front elevational view of a case for an ophthalmic mounting showing my new design.

Fig. II is a rear elevational view of the case shown in Fig. I.

Fig. III is an end view of the case.

The characteristic features of my design are shown in full lines in the drawing.

I claim:

The ornamental design for a case for an ophthalmic mounting, substantially as shown and described.

HERMAN F. HUTTEMEYER.
